INVENTOR
Joseph Berg,
BY
Harold D. Penney ATTORNEY

UNITED STATES PATENT OFFICE

JOSEPH BERG, OF LONG ISLAND CITY, NEW YORK; ESTHER BERG EXECUTRIX OF SAID
JOSEPH BERG, DECEASED

SOUND DEFLECTOR FOR PORTABLE PHONOGRAHS

Application filed October 27, 1928. Serial No. 315,498.

My present invention relates to an improvement in phonographs, and more specifically to portable phonographs and has to do with the provision of an improved form of sound deflector or horn.

One of the main advantages of my device is that, owing to its structure, it is of a compact form, as is necessary for the restricted dimensions of this type of phonograph, while 10 permitting of full amplification of the sound in volume and quality of tone.

A further advantage is the provision of means whereby the sound deflector may be adjusted to varying positions so as to direct 15 and concentrate the sound as desired.

These and other capabilities will be understood as the description proceeds and it is obvious that modifications may be made in the structure herein without departing from the 20 spirit hereof, or the scope of the appended claims.

In the drawings, Fig. 1 is a central sectional view of a characteristic portable phonograph, showing my device as applied.

25 Fig. 2 is a fragmentary plan view thereof with the cover removed to better show the application of the deflector.

Fig. 3 is a view similar to Fig. 1, with the cover open and the deflector shown in adjusted position.

30 Fig. 4 is a view similar to Fig. 2, showing the deflector in top view, fully open, as adjusted in Fig. 2.

Fig. 5 is an enlarged fragmentary sectional view of my deflector showing varying positions of adjustment.

My device comprises a terminal, sound directing deflector, generally denoted by 1, applied preferably to a portable type of phonograph, which consists of the usual casing 3, having a hinged cover 4, a turntable 5, a platform 6, upon which is rotatably supported the turntable motor, not shown, and the usual well known appurtenances, including in the 40 present instance, a sound box 6^a with its swivelled tone arm 7 leading to a tortuous, tapering amplifying tone tube or chamber 8. The tone chamber 8 is preferably mounted upon the under side of a platform 6, so that 45 in the usual style of structure the turntable

and its attached parts may be readily removed for inspection or repair.

The tone chamber at its larger end terminates flatly at the top plane of the platform 6, and is surmounted by a semi-cylindrical fixed tone deflector 9 which has at its opposite ends two end closing half round disks 10-10, which are provided with flat flanges 11-11 to afford a means of attachment to the top of the platform by means of screws 12-12.

At the center of the disks 10-10 is provided a pair of pivots 13-13 upon which is pivotally mounted a semi-cylindrical deflector hood 14, this being provided at its ends with a pair of end closure plates 15-15, whereby said hood may be pivotally attached to the end closing disks 10-10 and adjustably regulated for tone direction, as indicated in Fig. 5, wherein the fixed deflector 9 and the pivotal hood 14 are shown conformably assembled for radial relative adjustment. Between the deflector and hood is located a piece of felt 16, preferably affixed to the deflector to prevent vibration of the component metallic deflector hood and to provide also a frictional means to hold the hood in desired manually adjusted position. This figure also discloses, in dotted contour, different positions of adjustment of the hood for tone deflection. The hood may be flared 70 at its upper edge as at 17, as desired.

The hood and deflector are so mounted as to encompass the elongated sound opening 18 of the interior tapering tone chamber 8 at its point of intersection of the platform 6, and the rear end of the tone arm 7, and thus to direct the sound from the tone chamber upwardly and away from the rear of the phonograph, as illustrated by the arrows, Fig. 3.

In operation, when the cover of the phonograph is closed, as in Fig. 1, the hood 17 when open full, being relatively higher than the closed cover, is pushed backwardly and downwardly, the lower edge 19 thereof, Figs. 1 and 5, passing downwardly through a slot 20, provided in the platform 6, so that the said edge 19, is entered into the interior casing space below the platform.

When the cover 4 is lifted as in Fig. 3, the

pivoted hood may be raised to any desired position, at the will of the user, as indicated by the dotted positions A, Fig. 5, or the full position as in Figs. 3 and 4.

5 The foregoing detailed description has been given for clearness of understanding. Hence, no unnecessary limitations should be understood. Further, the appended claims should be construed as broadly as permissible 10 in view of the prior art, since many and various changes may be made without departing from the scope of the invention as defined in the broader claims.

What I claim and desire to secure by Letters Patent is:

15 1. In a device of the class described, a portable casing, a platform in a portion thereof, said casing having a cover, sound reproducing means associated with said platform one one side thereof, a tone chamber associated with the platform on the opposite side and cooperating with said reproducing means to amplify sound therefrom, said platform being provided with an aperture communicating with said tone chamber, a tone deflector on said platform adjacent said aperture, and a deflector hood movably associated with said tone deflector, said cover cooperating with said deflector hood, when in opened 20 position, to direct and concentrate sound issuing from said aperture.

25 2. In a device of the class described, a portable casing having a hinged cover, a platform in said casing adapted to support thereon sound reproducing means, said cover in closed position completely enclosing said means, means providing a sound amplifying chamber associated with the under side of said platform and connected to said sound 30 reproducing means, said platform having an aperture in a portion thereof, said aperture registering with a portion of said chamber, a tone deflector affixed to said platform and encompassing said aperture, a deflector hood 35 pivotably mounted on said tone deflector, said hood having a flared portion, said platform having a second aperture therein to receive another portion of said hood when said hood is pivoted.

40 3. In a portable phonograph a platform, to support on the face thereof a sound reproducing mechanism, an amplifying chamber, connected to said mechanism and positioned under said platform, said chamber having a sound outlet through said platform, an adjustable cylindrical sound deflector, passing 45 through a slot in said platform and extending over said outlet.

45 4. In a portable phonograph, a platform adapted to support on one face thereof sound reproducing mechanism, an amplifying chamber means on the other face of said platform, one end of said chamber being connected to said mechanism, the other end opening into an aperture in said platform, a sound

deflector surrounding said platform aperture, means associated with said deflector to retain the same in predetermined positions.

5. A phonograph comprising, a casing having a pivotable cover, a platform positioned at the top of said casing and adapted to support thereon sound reproducing mechanism, an amplifying tube in the space between said casing and platform, said tube having two open ends and being tapered from one end to the other, one of said ends being connected to said mechanism, the other end registering with an aperture in the platform, said platform having therein a second aperture between said first aperture and a casing wall, a pair of plates affixed to said platform, a semi-cylindrical tone deflector affixed to said plates and platform and encompassing said first aperture, a pivot plate movably mounted on each fixed plate, a semi-cylindrical deflector hood affixed at the ends thereof to said pivot plates for movement therewith, one side of said hood being flared, the opposite side passing through a slot in said platform when said hood is moved into non-deflecting position, a piece of felt positioned between said hood and deflector to retain said hood in a predetermined position, said cover, when in open position, cooperating with said hood, when in sound deflecting position, to direct and concentrate sound issuing from said first aperture.

6. A phonograph, including a platform, to support a sound reproducing mechanism thereon, a sound amplifying chamber, positioned under said platform, connected to said mechanism and opening into an aperture in said platform, an adjustable cylindrical sound deflector, having thereon a flared portion, extending over said aperture and passing through a slot in said platform, and means for adjustably supporting said deflector in position.

7. A sound deflector, to be used on a portable phonograph, having thereon a platform and a sound outlet through said platform, said deflector comprising a semi-cylindrical hood, passing through a slot in said platform, adjacent said outlet, and means to pivotally position said hood at said outlet, to extend over said outlet.

8. A sound deflector hood as in claim 7, said means including a stationary cylindrical sound deflector, a portion thereof being concentrical with said hood, said hood being manually adjustable in position with relation to said stationary deflector, and frictional means on said stationary deflector, for keeping said hood in position thereon.

9. A phonograph comprising, a casing having a cover pivoted at the rear wall of said casing, a platform affixed to said casing dividing said casing into an upper and a lower compartment, when said cover is in closed position, sound reproducing mechanism on said

platform and disposed in the upper compartment when said cover is closed, a sound amplifying chamber in the lower compartment, said chamber being connected to said mechanism, and opening into an aperture in said platform adjacent said rear wall, and a curvilinear sound deflector adjustably passing through a slot in said platform and extending over said aperture.

10 Signed at Long Island City, in the county of Queens and State of New York, this 25th day of October, A. D. 1928.

JOSEPH BERG.
